UNITED STATES PATENT OFFICE.

JEANNE D'ETREILLIS, OF NEW YORK, N. Y.

DESIGN FOR A CORSET COVER.

Application filed November 2, 1923. Serial No. 7,662. Term of patent 3½ years.

To all whom it may concern:

Be it known that I, JEANNE D'ETREILLIS, a citizen of France, and a resident of the city, county, and State of New York, have invented a new, original, and ornamental Design for Corset Covers, of which the following is a specification, reference being had to the accompanying drawing, forming part thereof.

The figure represents a plan view of a corset cover embodying my new design.

I claim:

The ornamental design for a corset cover, as shown.

JEANNE D'ETREILLIS.
